UNITED STATES PATENT OFFICE.

OSCAR CORDIER LEVRAY, OF CALAIS, FRANCE.

APPARATUS FOR CUTTING OR SHAVING LOOSE THREADS OFF TULLE, LACE, EMBROIDERY, AND THE LIKE.

946,904.

Specification of Letters Patent. Patented Jan. 18, 1910.

Application filed June 18, 1909. Serial No. 503,039.

To all whom it may concern:

Be it known that I, OSCAR CORDIER LEVRAY, a citizen of the French Republic, residing at 29 Place de la République, Calais, 5 Pas-de-Calais, France, have invented certain new and useful Improvements in Apparatus for Cutting or Shaving Loose Threads Off Tulle, Lace, Embroidery, and the Like, of which the following is a specification.

10 This invention relates to a mechanical device with an oscillating cutting blade provided with a handle which enables it to be moved by hand over the surface of tulle, lace, embroidery and the like for the purpose of cutting or removing the loose or 15 stray threads which are found therein.

It consists in providing the serrated parts 20 of the fixed counter blade and of the oscillating cutting blade with a guard in order to prevent the teeth of these devices from penetrating and tearing the fabric when the workman moves the apparatus over its surface. This guard not only covers the points 25 of the teeth but also the bottom and the top of the teeth of the oscillating cutting blade. The guard or sheath consists of a thin metal plate which is secured to the lower face of 30 the fixed blade and folded or bent over the ends of the teeth, the bend having a series of transverse slots opposite the gaps in the blades.

The invention consists likewise in a rotary brush arranged above the protecting sheath. When this brush rotates the ends of the 35 hairs thereon come in contact with the open part of the sheath and push against the loose threads of the fabric, bringing them into contact with the cutting blade. This brush is rotated by a mechanical device 40 which transmits its motion to the shaft that controls the cutting blade, so that the movements of the brush and of the cutting blade are simultaneous.

In the accompanying drawing, Figure 1 45 is a vertical section through $\alpha\alpha$ in Fig. 2 of the whole hand manipulated cutting device one of the arms supporting the rotary brush being omitted. Fig. 2 is a horizontal section through yy in Fig. 1, the brush and the arms 50 which support it being shown in plan. Fig. 3 is a side elevation of the various parts forming the cutting device. Fig. 4 illustrates the mounting of the fixed blade of the oscillating cutting blade and of the guard 55 or sheath as seen from above. Fig. 5 repre-

sents the fixed blade furnished with the guard or sheath as seen from below.

This mechanical cutting device which is of a well-known form is provided with a frame A on to which a hollow handle B is 60 screwed which enables the device to be operated. To the bottom of the frame a fixed blade 1 is attached above which a cutting blade 3 is mounted to oscillate on a pin 2. The inclined edges 4 of the fixed blade (Fig. 65 5) engage in grooves of the same shape formed in the foot of the frame A. The fixed blade is retained in position against this foot by a lateral screw 5. The pin constituting the axis of oscillation of the blade 70 3 is formed of the head 2 of a screw the stem of which is screwed into the plate 3, the head lodging in a cylindrical bottom part 6 provided in the end of the fixed blade.

In the vertical and longitudinal axis of 75 the frame A is a cylindrical bore 8 of enlarged diameter at the lower end 9 arranged to receive an eccentrically bored spindle 10. The upper part 11 of the spindle 10 which projects above the frame A is of rectangular 80 form and has a spherical enlargement at the top 12 of a larger diameter than the hole 8. The eccentric bore 13 extends through the greater portion of the spindle 10 and receives a spiral spring 14 and a spherical ended plug 15 which bears upon the spherical end of a rod 16 which terminates at its other end in a grooved foot 17 in which the stem of the cutting blade 3 is placed. The upper rectangular part 11 of the spindle 10 is fit- 85 ed into the hollow or sleeve of a flexible shaft C centered in the axis of the hollow handle B. The rotary motion communicated by this flexible shaft to the spindle 10 effects the oscillating movement of the rod 16 90 and of its foot 17 which transmits it to the blade 3.

The spindle is furnished with a ring of helicoidal teeth 18 arranged in the enlarged part 9 of the bore 8. These teeth engage 100 with a helicoidal toothed wheel 19 formed on one of the ends of a sleeve 20 which rotates idly around the cylindrical stem of a horizontal stud bolt 21 screwed into the frame A. The other end of the sleeve 20, 105 which comes flush with the tangential part of the frame A is cut away so as to form a spur-gear 22 which engages with a pinion 23 mounted on the outside against a horizontal arm 24 forming part with the frame 110

A. Against the exterior of this arm two other pinions 23, 26 are mounted which engage one with the other. The extreme pinion 26 is mounted on the horizontal shaft 27 of a brush 28. The opposite end of the horizontal shaft 27 is mounted in another horizontal arm 29 placed opposite the arm facing the tangential part of the frame A with which it forms part. A counter-plate 30 in which the shafts of the pinions 23, 25 and 26 are pivoted is arranged on the exterior of these pinions. It is fixed on the inner face of the arm 24 by a screw 31.

The rotary movement of the spindle 10 which is communicated to it by the flexible shaft C is transmitted to the brush 28 by the helicoidal gear 18, 19 and the spur gear 23, 25, 26 so that the cutting blade and the brush are simultaneously actuated through 20 the flexible shaft C.

The guard or sheath is formed of a thin piece of metal 32 fixed against and on to the lower face of the fixed blade 1 by two screws 33. This guard plate is a little wider than the fixed blade opposite its teeth. It is bent at the end of the said teeth and turned back very near the teeth of the cutting blade 3 and terminates a little beyond the roots of the teeth of that blade. The 30 guard 32 is slotted at 34 forming a series of notches extending from the bend inward. The parts left between the slots form teeth preferably of less depth on the lower face opposite the teeth of the blade 1 than on the 35 upper face opposite the teeth of the blade 3. The bent part of the plate 32 is closed laterally at 35 over a small portion of its length beginning from its outer curve.

The loose threads of the fabric which are 40 cut off when the lower face of the cutting tool is moved over the surface of the fabric, are forced into the open part of the guard by the rotary brush 28 and as soon as they enter they are cut off, owing to the reciprocating movement of the cutting blade 3. The guard being slotted only over a portion of its width, opposite the blades and its lateral extremities being rounded and closed, the loose threads cannot get under 50 the guard or penetrate into the same or the blades. Thus the workwoman cannot tear the tulle or the lace when moving this blade over the surface.

What I claim and desire to secure by Letters Patent is:—

1. A hand manipulated cutting tool of the class described comprising a toothed fixed or counter blade, an oscillating toothed cutting blade, means for imparting motion

to the oscillating blade and a thin metal 60 guard plate bent back over the teeth of the blades and slotted at the bend to form teeth over a portion of its width corresponding to a little more than the width of the toothed part of the cutting blade, the cut-away part of the guard being narrower at the bottom than at the top and its curved portion being closed laterally.

2. A hand manipulated cutting tool of the class described comprising a toothed 70 fixed counter blade, an oscillating toothed cutting blade, a flexible shaft, an eccentrically bored spindle connected with the shaft, a rod in the bore having a bridge piece or foot adapted to embrace the cutting-blade, 75 a thin metal protecting sheath fixed against the bottom of the fixed blade and bent and turned up at the end of the teeth of the same and near the teeth of the oscillating cutting blade and having a notched part 80 opposite the point of the teeth in the blades, a rotary brush arranged between two arms placed tangentially to the frame of the cutting-tool with which they form part, the shaft of this brush being placed parallel to 85 the plane of the fixed blade and actuated by means of the spur gear mounted outside on one of the two arms of the frame, the said gear being actuated by the eccentrically bored spindle through the medium of helicoidal gear substantially as described.

3. A hand manipulated cutting tool comprising a combination of a frame provided with a handle, an eccentrically bored spindle mounted therein, a rotary flexible shaft connected with the spindle, a rod mounted eccentrically in the spindle and terminating in a bridge piece or foot, a movable toothed cutter blade adapted to be oscillated through the said foot, a toothed counter 100 blade fixed by a screw on the bottom of the frame, a guard covering the points of the teeth of the blades and slotted over a portion of its width opposite the points of the teeth in the blades, a rotary brush arranged 105 between the two arms placed tangentially to the foot and on one of the sides of the frame and adapted to rotate above and against the guard, being mounted on a shaft which receives the rotary motion of the 110 spindle through the medium of helicoidal and spur gear substantially as described.

In testimony whereof I have affixed my signature, in presence of two witnesses.

OSCAR CORDIER LEVRAY.
